COMBINED HOLDER AND CHARGING UNIT FOR ELECTRIC TOOTHBRUSH OR THE LIKE

Austin E. Cox, Wadsworth, Ohio, assignor to Dominion
Electric Corporation, a corporation of Ohio

Filed Oct. 18, 1965, Ser. No. 87,560

Term of patent 14 years

(Cl. D4—3)

Fig. 4

Fig. 1

Fig. 2

Fig. 3

FIGURE 2 is a side view of the same, the opposite side being similar in appearance;

The toothbrush handle disclosed in broken lines in FIG. 2 is shown for illustrative purposes only.

I claim:

The ornamental design for a combined holder and charging unit for electric toothbrush or the like, substantially as shown and described.
